HINGED SASH STRUCTURE

Benoit M. Singleton, Marshall, Mich., assignor to Woodlin Metal Products, Marshall, Mich., a corporation of Michigan

Application February 16, 1953, Serial No. 337,173

9 Claims. (Cl. 189—69)

The present invention relates broadly to operable closure means for an opening, and in its specific phases to a special form of operating mechanism for a hinged window or ventilator apparatus.

Several different types of crank-actuated operating means have been devised for windows and ventilators of buildings and movable compartments, such as house trailers, particularly hinged ventilators used in the roof and small hinged windows used in the side walls near the roof of the latter. Such operating means in general have not tightly closed the hinged windows or ventilators at the edge remote from their hinge mountings, allowing entrance of driving rain, and outside air in addition to the escape of heat in winter. It was a recognition of these difficulties and shortcomings of the prior art which lead to the conception and development of the present invention.

Accordingly among the objects of the present invention is the provision of a new and improved operating means which will insure tight closing of a window or ventilator at the edge thereof remote from its hinge mounting means, thus making it possible to have a tight seal entirely around the window or ventilator.

Another object of the present invention is to provide a swingable arm operable by means of a hand crank, and a link connecting said arm with the hinged window sash or ventilator to push this sash or ventilator open when the crank is turned in one direction and to pull it shut when said crank is turned in the other direction. These elements are not uncommon, but the present invention is designed to provide a new and improved construction and relation whereby the link acts as a lever during the final closing of the sash or ventilator to force the edge thereof remote from the hinged edge tightly in against the frame.

A further object of the invention is to provide a novel construction which will be simple and inexpensive yet efficient and reliable.

Still further objects and advantages of the present invention will appear as the description of the invention proceeds.

To the accomplishment of the foregoing and related ends, the invention, then, consists of the means herein-after fully described and particularly pointed out in the claims, the annexed drawings and the following description setting forth in detail certain means for carrying out the invention, such disclosed means illustrating, however, but one of various ways in which the principle of the invention may be used.

In the annexed drawings:

Figure 1 is an inner side elevation of a house trailer window embodying the invention.

Figure 2 is an enlarged vertical sectional view on line 2—2 of Figure 1, looking in the direction of the arrows and showing the sash closed.

Figure 3 is an end elevation, partly broken away and in section, showing the sash partly opened.

Figure 4 is a fragmentary edge view of the push and pull link, and a portion of the swingable arm connected to said link.

Figure 5 is a perspective view of a channel bar, shown in the assemblies of Figures 2 and 3, which in use is secured to the sash and pivotally connected to the link.

The invention will be described in connection with a window and its sash, but the term "sash" is to be interpreted as comprehending not only an actual sash but any

2

swingable closure means which might be used in place thereof to provide a closure for an openable passageway such as in a ventilator instead of an actual window. Also, the term "window frame" is to be considered as comprehending a frame of an openable passageway closure member such as a ventilator as well as a frame for a window.

A metal window frame is shown at 6, said frame having an outer peripheral attaching flange 7, an inner peripheral flange 8 and a continuous side wall 9 connecting said flanges 7 and 8. The flanges 7 and 8 for most uses are substantially parallel, and the side wall 9 will ordinarily space flange 8 inwardly from flange 7.

A sash 10, for a flush assembly, is closable against an inner offset portion of the flange 7 of the frame 6, Figures 2 and 3, and is connected at its upper edge with said flange by a hinge 11. The sash shown comprises a metal frame 12, a pane 13, and a rubber gasket 14 connecting said frame and pane, said gasket ordinarily being of general H-shape in cross-section to provide channels snugly receiving the adjacent edge portions of said frame 12 and pane 13. The frame 12 is provided with a suitable gasket 15 at its inner face for tight sealing contact with the flange 7.

Centrally between the ends of the sash frame 12, and in front of bar 20, a vertical channel bar 16 is provided at the inner side of said sash frame. The side flanges of this channel bar 16, Figure 5, are denoted at 17 and the flange-connecting portion at 18. This portion 18 preferably lies against the inner side of the pane 13, Figure 2, and its ends 19 extend into the channel of the gasket 14 which receives the edges of said pane. The channel bar 16 is thus secured to the sash frame 12 in a simple and convenient manner.

A central flat bar 20 vertically spans the frame 6 in opposed relation with the channel bar 16 and is secured by rivets or the like 21 to the flange 8 of said frame 6. Between its ends, this bar 20 is formed with a slot 22.

A casing 23 is secured with screws 24 to the bar 20 and contains a worm wheel 25, which is preferably segmental as shown, and worm gear 26, said worm gear having a shaft 27 to which an operating crank 28 is secured. The worm wheel 25 is provided with an arm 29 which extends through the slot 22 of the bar 20, said arm occupying an upstanding vertical position between the side flanges 17 of the channel bar 16 when the sash 10 occupies its closed position, as seen in Figure 2. Also disposed between these flanges 17 is a push-and-pull link 30 which occupies a vertical position when the sash is in closed position. The lower end of the link 30 is connected with at least one of the flanges 17 of the channel bar 16 by a pivot 31. Near its upper end, the link 30 is connected with the arm 29 by a pivot 32. Thus, swinging of the arm 29 by turning the crank 28, will cause the link 30 to push or pull upon the channel bar 16, thereby opening or closing the sash 10 as required.

At its upper end 33, the link 30 projects above the pivot 32 to lie against an outwardly facing portion of the frame 6 as shown in Figure 2 when the sash 10 occupies its closed position. In the present showing, this outwardly facing portion is an abutment plate 34 secured to the outer side of the flange 8 of the frame 6. The link end 33 comes into contact with the abutment plate 34 when the sash 10 is almost closed. Consequently, the final sash-closing movement of the arm 29 (in the direction of the arrow on pivot 32 in Figure 2) will swing the link 30 about said abutment plate 34 as a fulcrum, causing the lower end of said link to move in the direction of the arrow on pivot 31. Thus, the link 30 becomes a lever and forcibly prys the lower edge of the sash 10 tightly in against the flange 7 of the frame 6. This effectively overcomes the lack of tight closing at the lower edge of the sash as in prior constructions.

From the foregoing, it will be seen that novel and advantageous construction of the closable assembly has been provided for attaining the desired ends which particularly involve the tight closing of the assembly, and while preferences have been disclosed, it is to be understood that variations may be made within the scope and principles of the invention as set forth. Also, it is to be

understood that such terms as "inner," "outer," "upper," "lower," and "vertical" as herein used, are illustrative rather than limiting.

Other modes of applying the principle of my invention may be employed instead of the one explained, change being made as regards the apparatus herein disclosed, provided the means stated by any of the following claims or the equivalent of such stated means be employed.

I therefore particularly point out and distinctly claim as my invention:

1. In a window or ventilator having a frame, a sash closable against the outer side of said frame, and hinge means connecting one edge of said sash with said frame; an operating arm pivotally mounted on said frame for swinging movement in a plane transverse to the axis of said hinge means, said arm extending toward the hinged edge of said sash when the latter is in closed position, a push and pull link, one pivot near one end of said link and connecting the latter with said operating arm, and a second pivot connecting the other end of said link with said sash, said one pivot connected to said operating arm being disposed toward the hinged edge of the sash and said second pivot being disposed toward the opposite edge of said sash, said one end of said link projecting beyond said pivot connected to said operating arm, said frame having an outwardly facing portion against which said one end of said link comes to rest immediately prior to complete sash closing; whereby the final sash closing movement of said operating arm will swing said link about said outwardly facing portion as a fulcrum, causing said other end of said link to inwardly pull the edge of the sash remote from said hinge means.

2. A structure as specified in claim 1; said frame having a bar upon which said operating arm is mounted, said bar extending across said frame from the hinge-carrying side of same to the side opposite thereto, a worm wheel to which said arm is secured, a worm gear meshing with said worm wheel, means for rotating said worm gear, and a support member mounted on said bar and carrying said worm gear and worm wheel.

3. A structure as specified in claim 1; said frame having a bar upon which said operating arm is mounted, said bar extending across said frame from the hinge-carrying side of same to the side opposite thereto, a segmental worm wheel to which said arm is secured, a worm gear meshing with said segmental worm wheel, a crank operated means for rotating said worm gear, and a casing mounted on said bar and containing and rotatably mounting said segmental worm wheel and said worm gear.

4. A structure as specified in claim 1; said sash having a sash frame, a pane, and a gasket connecting said pane to said sash frame; said sash also having a bar to which said second pivot connects said link, said bar being mounted at the inner face of said sash and extending from the hinged edge thereof to the opposite side of same for unitary movement therewith.

5. A structure as specified in claim 1; said sash having a sash frame, a pane, and a channeled gasket connecting said sash frame and pane; said sash also having a bar to which said second pivot connects said link, said bar lying against said pane and extending from the hinged side of said sash to the opposite side of same and having its ends disposed in the pane-holding channel of said gasket, whereby said bar and said sash frame are unitarily connected.

10. 6. A structure as specified in claim 1; said sash having a sash frame, a pane, and a channeled gasket connecting said sash frame and pane; said sash also having a channel bar which extends from the hinged side of said sash to the opposite side of same, said channel bar having two side flanges and a portion connecting said flanges and through at least one side flange of which said second pivot connects said link, the flange connecting portion of said channel bar having extended ends disposed in the pane-holding channel of said gasket, whereby said bar and said sash frame are unitarily connected.

15. 7. In a window assembly including a window frame with a window sash hingedly mounted thereon, said window sash having a frame, a pane, and a channeled gasket connecting said pane and frame; a bar spanning said sash frame crosswise from the hinged side of same and having its ends inserted into the pane-holding channel of said gasket, whereby said bar and frame are unitarily connected, and sash operating means carried by said window frame and pivotally connected to said bar.

20. 8. A structure as specified in claim 7; said bar being a channel bar having a pair of side flanges and a flange connecting portion with the ends of the flange-connecting portion of said channel bar which engage said gasket being extended beyond the ends of the side flanges of said channel bar, and said sash operating means including a push and pull link with one end of same being pivotally connected with at least one of said side flanges.

25. 9. A structure as set forth in claim 8; said sash operating means having in addition to said push and pull link, an operating arm, means for mounting said operating arm on said bar extending across said window pane, said mounting means including a worm wheel to which said arm is secured, a worm gear meshing with said worm wheel, means for rotating said worm gear, and means for 30 pivotally connecting one end of said operating arm to the end of said push and pull link opposite to that connected to the channel bar of said window sash, whereby operation of said means for rotating said worm gear will pivotally move said window sash.
